A. HAIGH ET AL

PROCESS OF MAKING CARBON AND OTHER COATED PAPERS

Filed Sept. 7, 1922

Patented Dec. 1, 1925.

1,563,978

UNITED STATES PATENT OFFICE.

ALFRED HAIGH AND HAROLD RAVEN HART, OF STAFFORDSHIRE, ENGLAND.

PROCESS OF MAKING CARBON AND OTHER COATED PAPERS.

Application filed September 7, 1922. Serial No. 586,779.

To all whom it may concern:

Be it known that we, ALFRED HAIGH, a subject of the King of Great Britain, residing in Staffordshire, England, and HAROLD RAVEN HART, a subject of the King of Great Britain, residing in Staffordshire, England, have invented certain new and useful Improvements in Processes of Making Carbon and Other Coated Papers, of which the following is a specification.

This invention relates to improvements in and relating to carbon and other coated papers and carbonizing papers and refers primarily to the so-called carbon papers such as are used for duplicating purposes upon typewriting machines, in salesmen's books, and for other purposes, and in which one or both sides or surfaces are coated with the desired composition.

The present invention relates to papers of the above character in which only one side or surface is coated.

The term "carbonizing paper" used herein is intended to apply to the plain or untreated paper.

In the manufacture of carbon papers as at present generally conducted the paper in the form of a continuous web of thin paper is first coated and afterwards cut up into sheets of the desired dimensions.

In view of the thinness of the paper a certain amount of care is required in the handling thereof in order to avoid tearing or damaging same, and further care is necessary to prevent the composition from getting upon that side of the paper which is to remain untreated.

Where a thin paper is employed such as that referred to it frequently happens that there are small holes in said paper through which the coating material will pass to the back of the sheet and extend more or less thereover, in which case not only does the paper stick to the rollers but the coating composition thus conveyed to the rollers will "set-off" or stain the paper which follows.

The present invention has for its object to overcome the aforesaid objections attending the present method of manufacture of carbon papers, and further to simplify and expedite the production of such paper.

In the co-pending application Serial No. 586,772, it has been proposed to employ two sheets of paper separably adhered together and to coat one or both of the outer surfaces thereof, the second sheet preventing the pas-

sage of the coating substance to the back of the sheet or sheets as the case may be.

According to the present improvements in order to prevent the staining or marking of the backs of the coated sheets the said sheets may have interposed between them a third plain sheet or if desired two plain sheets may be interposed between those having the coated surfaces whereby each single carbon sheet may be provided with a backing or interleaving sheet separable from the coated sheets before use, and which sheets would also prevent "set-off" whilst the sheets were stored.

The composition can be applied first to one side of the paper and then to the other in two separate operations or both sides of the paper may be simultaneously coated by any of the methods employed or capable of being employed for producing a double sided carbon paper. By this means two carbon sheets may be produced instead of one, and further any risk of the composition passing through holes in the paper and extending to the uncoated surface is prevented.

The papers may be all of the same weight or thickness or one paper may be heavier than the other.

The attachment of the papers one to another may be effected by bringing the sheets or webs of paper together whilst one or more are in a moist condition and causing them to adhere by pressure.

A suitable means for separating the carbon coated papers is shown in the accompanying drawing in which Figure 1, is a diagrammatic view showing a means for separating a duplex web the outer surfaces of the sheets of the web being coated, and for showing means for separating a quadruplex web, the outer sheets being coated on their outer surfaces and the two intermediate or interleaving sheets being uncoated and separately secured to the outer sheets and to each other.

Figure 2, is a fragmental sectional diagrammatic view, on an enlarged scale, showing the separation of a duplex web of carbon coated paper into two sheets coated on one of their surfaces.

Figure 3, is a fragmental sectional diagrammatic view, on an enlarged scale, showing the separation of a web of coated paper consisting of two sheets coated on their outer surfaces and having between their inner un-

coated surfaces and separable therefrom an intervening or interleaving uncoated sheet, and

Figure 4, is a fragmental sectional diagrammatic view, on an enlarged scale, showing the separation of a quadruplex web consisting of two sheets coated on their outer surfaces and two intermediate or interleaving uncoated sheets secured to the uncoated surfaces of the outer sheets and separable therefrom and from each other, the intermediate sheets being shown in course of separation from each other and remaining secured to the outer sheets for protecting the outer sheets.

Similar reference characters denote similar parts throughout the several views.

Referring to Fig. 1, and considering the web as consisting of two sheets represented by the full lines and coated on their outer surfaces and for purposes of explanation disregarding the dash and dot lines of the figure, the duplex web A is passed between the rolls BB, which are moved by the web, the sheets represented by the full lines being separated at the nip between the rolls, as seen in Fig. 2, and passing around the guide rolls CC are wound upon the mandrels DD.

Again referring to Fig. 1, and considering the quadruplex web as consisting of two coated outer sheets shown in full lines and of two intermediate or interleaving uncoated sheets shown by the dot and dash lines, the outer coated sheets A¹, A² are separated at the nip between the rolls BB and guided by the rolls CC are wound around the mandrels DD, while the uncoated sheets A³, A⁴ are carried between the rolls EE, and separated at the nip between these rolls and passing around the guide rolls FF are wound around the mandrels GG, thus providing two sheets of coated paper separated from the uncoated sheets.

Referring to Fig. 4, the uncoated sheets A³, A⁴ of the quadruplex web are separated from each other at the nip of the rolls BB, and guided and rolled with one of the coated sheets each becomes a protective backing for

a single coated sheet which is guided and wound by the rolls CC and the mandrels DD.

Referring to Fig. 3, the web consists of two coated outer sheets A¹, A² having an intermediate or interleaving uncoated sheet A⁵ separably secured therebetween, the separation of the outer sheets from the intermediate sheet, being at the nip between rolls such as BB, the separated sheets being guided and wound as described for the duplex web, while the intermediate sheet is carried around a single roll such as E and wound around a single mandrel such as G, shown in Fig. 1.

The utility of the present invention lies not only in the reduction of cost when the two papers are coated together, but also in the greater ease with which the double paper is handled, and further in that when this invention is used there is no possibility of surplus composition deposited accidentally on the "back" or plain side of the paper through pin holes in the paper or otherwise.

Any other coating process besides carbonizing may be used or applied to this paper.

Claims:

1. A process including moistening and superposing at least three webs of paper in intimate contact to cause the webs to cohere in a manner to permit ready separation of the webs; and coating the exposed face of the outside webs after the webs have been superposed, leaving the unexposed faces of the webs uncoated.

2. A process including superposing at least four webs of paper in a manner to permit ready separation of the webs, the inner webs being thicker than the outer webs; and coating the exposed face of one of the outside webs, leaving the unexposed faces of the webs uncoated.

In testimony whereof we have hereunto set our hands.

ALFRED HAIGH:
HAROLD RAVEN HART.
